FOLDING CLOTHES DRIER

Harry L. Griffin, New York, N. Y., assignor to
Dry-Or-Shade, Inc., New York, N. Y., a corpora-
tion of New York

Application March 11, 1950, Serial No. 149,199

3 Claims. (Cl. 211—178)

1

This invention relates to combination sun shades and clothes driers.

Among the objects of the present invention it is aimed to provide an improved combination sun shade and clothes drier of the type illustrated in my co-pending application Ser. No. 130,044, filed November 29, 1949, and co-pending applications Ser. No. 758,962 filed July 3, 1947, Ser. No. 23,571 filed April 27, 1948, and Ser. No. 86,517 filed April 9, 1949, all referred to in co-pending application Ser. No. 130,044, in which there is provided a plurality of arms for supporting not only the clothes lines, but also the sun shade or canopy, the present invention being characterized by the fact that any one of the arms may with facility be lowered partly or completely either in the interest of privacy should the combination be used in a public park, beach, or even the lawn of a home immediately adjoining the lawn of another home, or to intercept the sun rays particularly during the early morning or late afternoon.

It is still another object of the present invention to provide a construction for supporting and manipulating one or more arms of a combination sun shade and clothes drier which is not only easy to operate and easy to assemble, but which can be manufactured at a comparatively low cost.

It is still another object of the present invention to provide an extension particularly adapted for an arm of the improved type aforesaid, which is not only easy to operate and easy to assemble, but which can be manufactured at a comparatively low cost.

It is still another object of the present invention to provide an improved means for securing the canopy or awning in place on the arms of the improved type aforesaid, which is not only easy to operate and easy to secure in place, but which can be manufactured at a comparatively low cost.

It is still another object of the present invention to provide an improved combination sun shade and clothes drier having a plurality of arms for supporting not only the clothes line sections, but also the sun shade or canopy, and a plurality of links operatively connected to the arms which may, with facility, be actuated to lower the arms completely for storage or shipping purposes.

These and other features, capabilities, and advantages of the present invention will appear from the subjoined detailed description of one specific embodiment thereof illustrated in the accompanying drawings, in which

Fig. 1 is a front elevation partly in section

2

of a combination sun shade and clothes drier made according to the present invention.

Fig. 2 is a fragmental detail showing one of the arms partly lowered.

Fig. 3 is an enlarged fragmental section showing the connection between an arm and a supporting link in fully extended position.

Fig. 4 is a fragmental section similar to Fig. 3 showing the connection released preparatory to lowering the arm, or preparatory to positioning the arm in the extended position shown in Fig. 3.

Fig. 5 is a section on the line 5—5 of Fig. 3.

Fig. 6 is an enlarged perspective of the parts 15 of the main supporting bracket for the arms and links of the combination.

Fig. 7 is a plan of the combination with the canopy removed.

Fig. 8 is a fragmental side elevation of the 20 outer end of an arm with its associated extension shown in full lines in contracted position and shown in dash and dot lines in extended position.

Fig. 9 is an enlarged section on the line 9—9 25 of Fig. 8.

Fig. 10 is a perspective of the spring shown in Fig. 3.

In the embodiment shown the main post 1 may 30 be provided with any suitable tapered pin for securing the post 1 in the ground, as an instance the pin 2 having the shoulder 3 and the tapered end 4. The shoulder 3 in the present instance engages the lower free end of the post 1 and is interposed between the lower free end of the 35 post 1 and the upper end of the tubular insert 5 secured in the ground by any suitable means, such for instance as the cement block 6.

Ordinarily the post 1, composed of tubular stock, requires no machining except merely to 40 cut the same to the length required, nor does it require the formation of any holes therein for the mechanism to be attached to it now to be described.

If it is desired to have a table associated with 45 the same, it is only necessary to provide an opening in the center of the table top 7 of the table 8, through which the post 1 passes. The table top in turn may be connected to and supported by four lengths of tubular or round stock 9, somewhat U-shaped as shown, which are connected to one another by two collars 10 and 11 through which the post 1 passes. When the table 8 is not associated with the post 1, it will, of course, be supported by the legs 9 in the conventional way. In turn, the combination sun shade and

clothes drier obviously can be used without the table, and to this extent the table is merely an accessory.

The upper end of the post 1 may have secured thereto a cap 12 as shown, although obviously the cap 12 is ordinarily unnecessary, so that as aforesaid the post 1 may consist of a plain length of tubular stock without any holes drilled therein or any machining except cutting the same to the length desired.

As particularly shown in Fig. 6, the bracket 13 for supporting the arms and links of the sun shade consists essentially of four wing forming plates 14, 15, 16 and 17. These wing forming plates are substantially identical, having an intermediate curved portion 18 and two wings 19 and 20 extending therefrom. The wing portion 19, as an instance of the plate 16, has an opening, not shown, which registers with the opening 21 of the wing 20 of the plate 15. In turn, the wing 19 of the plate 17 has an opening 22 registering with the opening 21 of the wing 20 of the plate 16, the wing 19 of the plate 15 has an opening 22 registering with the opening 21 in the wing 20 of the plate 14, and the wing 19 of the plate 14 has an opening similar to the opening 22 not shown, registering with an opening similar to the opening 21 in the wing 20 of the plate 13.

The wings 19 and 20 of each plate in turn have intermediate recesses 23, in the present instance about one-third from the bottom of each plate. These recesses 23 are primarily provided to form the horns or projections 24. Each recess has an inwardly sloping edge 25 continuing in an outwardly sloping edge 26 and then in the inner edge 27 of the horn or projection 24. The projection 24 is preferably enlarged, that is, provided with a protruding portion 28 at its upper end.

In addition to the recesses 23, each wing 19, 20, has an opening 29 near the bottom thereof. The openings are formed in the inwardly projecting plate portions 30, see particularly Fig. 6. The plate portions 30 of adjacent wings 19 and 20 are formed in order to provide a space that is narrower than the space provided between each pair of adjacent wing portions 19 and 20 at the upper ends thereof. The openings 29 of each pair of wings 19 and 20 in turn also register with one another.

The openings 21 and 22 of each adjacent pair of wings 20 and 19, respectively, are provided to receive a pivot pin 31 which extends through the parallel walls 32 and 33 of an arm 34. In turn, the openings 29 of adjacent wings 19 and 30 receive the pivot pin 35 extending through the parallel walls 36 and 37 of a supporting link 38. There are four sets, including an arm 34 and a link 38, to be supported between the four sets of wings 19, 20.

After the arms 34 and 38 are so pivotally connected to the plates 14, 15, 16 and 17, the unit may be positioned on the post 1 as shown in Fig. 1. To support the bracket 13 and its associated arms and links in the position shown in Fig. 1, there is provided a sectional collar 39 composed of two plates having adjacent ears 40 secured to one another on one side of the post 1 and a wing nut 41 extending through the ears of the plates on the other side of the post 1. This sectional collar is frictionally secured in place by the wing nut 41.

In order to obtain an additional bearing surface for the bracket 13, a washer, such as the washer 139, is slipped over the post 1 into supporting engagement with the collar 39 and then the bracket 13 slipped over the post 1 into supporting engage-

ment with the washer 139, the washer 139 and collar 39 thus serving as a supporting abutment for the bracket 13.

Obviously the wing nut 41 of the collar 39 may, with facility, be actuated to free the collar 39 and enable the user to move the collar 39 to the level desired on the post 1. The level selected will, of course, ordinarily depend upon the height of the user, since obviously the taller person might prefer the highest position on the post 1 for the bracket 13, and the shorter person a lower position on the post 1 in the interest of manipulating the canopy 55 and the clothes line sections 47 and 73.

Each arm 34, see Fig. 5, has a fin 42 extending upwardly from the web 43 connecting the parallel walls 32 and 33. The lower ends of the walls 32 and 33 have inwardly extending flanges or ledges 44 and 45, respectively. The fin 42 of each arm, see particularly Fig. 2, is provided with a plurality of openings 46 to receive the clothes line sections 47, see Fig. 7. The links 38 are preferably chambered or tubular but flattened out as shown in Figs. 5 and 6 to form the parallel walls 36 and 37 through which the pin 35 extends. At the outer end of each link 38 through the parallel walls 36 and 37 adjacent the lower edge of the link 38 there extend the free ends of a ring 48. Each link 38, see Figs. 3 and 4, has a recess 49 formed in the upper outer end thereof to receive either the pin 50 or the pin 51 or no pin at all. In the position shown in Fig. 1 in full lines the links are shown in their outstretched or highest position where the recess 49 of each link engages a pin 50. In Fig. 2 one arm is shown with the recess 49 of the link 38 engaging the pin 51, and in dash and dotted lines in Fig. 1 a link 38 is shown adjacent the post 1 where its recess 49 does not engage any pin, that is, where the end of the link or the recess 49 is positioned beyond the outermost pin 51 in the arm 34.

In order resiliently to anchor a link 38 either in position to engage a pin 50 or to engage a pin 51, there is provided a U-shaped spring 52, the free ends of which extend into the parallel walls 36, 37 of a link 38, in the present instance just rearwardly of the recess 49. This U-shaped spring 52 has two legs each bent back upon itself to form a V shape consisting of the portions 53, the free ends of which extend into the parallel walls 36 and 37, and the portions 54 which rest on the ledges 44, 45 as shown in Figs. 3, 4 and 5, with the web 55 connecting the leg portions 54 extending across the free end of a link 38. The ring 48 is provided to pull the arm 38 downwardly from the position shown in Figs. 3 and 5, into the position shown in Fig. 4, where the free end of the link with its recess 49 clears the pin 50 in the arm 34 so that the arm 34 may be depressed, as an instance into the position shown in Fig. 2 where the spring 52 will urge the arm 38 upward and cause the recess 49 to receive the pin 51, or else the spring 52 may be depressed long enough so that the outer end of the arm 38 clears both pins 50 and 51 and permits the link 38, and therewith the arm 34, to be suspended adjacent to the post 1 as shown in dash and dot lines in Fig. 1.

Since the collar 39, or when the washer 139 is used, the washer 139 supported by the collar 39, alone supports the bracket 13 on the post 1, as aforesaid, it is only necessary to move the collar 39 up or down the post 1 to the desired position, fasten the same by the wing nut 41, and the bracket 13 will move down or up with it to the position desired, and no adjustment is otherwise

required to determine the position of the links 38 relative to the arms 34 other than the manipulation of the spring 52. In other words, the pivotal points for the arms and links are predetermined by the bracket 13.

The arms 34 in outstretched position with or without the clothes lines 47 may serve also to support the canopy or awning 55 which is preferably rectangular in outline with a depending apron 56, and provided with a central opening 57 to receive the upper end of the post 1 or the cap 12. Preferably, of course, the opening 57 of the canopy is reinforced by a grommet or the like.

At four equally spaced radially extending areas of the canopy 55 there are secured the brackets 58 provided with a wing nut 59. The brackets 58 are secured to the inner face of the canopy 55 by any suitable means, preferably by canvas patches 60, see particularly Fig. 9. These brackets have two lower protruding flanges 61 and 62 parallel to one another to receive the fin 42 of an arm 34. The wing nut 59 in the present instance, see Fig. 9, is shown as extending through the flange 62 so that it may frictionally engage the fin 42 and anchor the canopy in position. In other words, the canopy may be loosely placed upon the arms 34 and if there should be no wind, leave it so positioned. However, in order to guard against wind and the like, the brackets 58 and wing nuts 59 are provided to anchor the inner face of the canopy to the arms 34. As clearly appears from Fig. 8, the bracket 58 has an outer plate portion 63 which extends beyond the outer end of an arm 34 to clear the finger 64 of the extension 65 now to be described.

Each arm 34 is provided with an extension 65 shown in cross section in Fig. 9 as having a fin 66 extending upwardly therefrom, an enlargement 67 with slots 68 and 69 running parallel to the fin 66 and conforming to receive the flanges or ledges 44 and 45, respectively. From the enlargement 67 there depends the extended fin 70 provided with openings 71 and grommets 72 in such openings to receive clothes line sections 73. In the present instance the extension 65 has only two such openings 71 to receive only two clothes line sections 73. The fin 66 is provided with two recesses or notches 74 and 75 to receive the downwardly extending projection 76 of the finger 64. The finger 64 has an extension 77 extending beyond the outer end of an arm 34 as shown in Fig. 8 so that the same may be depressed to actuate the finger 64 about its pivot pin 78 to raise the projection 76 out of a slot 74 or 75. When the projection 76 is disposed in the outermost recess 74 of the extension 65, the extension will be in the retracted position shown in Figs. 1 and 2 and in full lines in Fig. 8. In turn, when the projection 76 rests in the innermost recess 75 of the extension 65, the extension will be disposed in the outermost or extended position indicated in dash and dot lines in Fig. 8.

The pin 78 on which the finger 64 is pivotally mounted, see Fig. 9, extends through the side walls 32 and 33 of the arm 34. Obviously, if the extension 77 of the finger 64 is depressed after the projection 76 clears the recess 75, the extension 65 may be entirely removed from slidable arrangement with the arm 34.

When the extension 65 is in the retracted position shown in Figs. 1 and 2, then the slack in the clothes line sections 73 may be taken up by looping portions thereof over the horns or projections 24 of the bracket 13, as shown in Fig. 7.

When in turn it is desired to remove one or more of the extensions 65 into the extended position, it is only necessary first to free the clothes line sections 73 from the horns 24, then to actuate the finger or fingers 64 and slide the selected extension or extensions 65 out into the position where their respective fingers 64 will cooperate with the slots 75. If there is still some slack in the clothes line sections 73 when one or more extensions 65 have been extended, then of course it is only necessary to take each such clothes line section and draw it over a horn or projection 24.

The canopy 55 may either be mounted on the arms 34 when the extensions 65 are retracted as shown in Fig. 1, or still remain connected to such arms when one or more extensions 65 are actuated into an extended position. In other words, if it is only desired to hang a few clothing items on the clothes line sections it is not necessary to free the canopy from the arms, but merely to extend one or more of the extensions 65 so that its clothes line sections are exposed to the sun light. Of course, obviously if the clothes items to be dried are sensitive to sun light, then it is unnecessary either to actuate the extensions 65 or to disturb the canopy 55, but merely to hang the clothes items on the clothes line sections covered by the canopy.

In turn, if the combination is to be used exclusively for drying clothes, the canopy 55 may be entirely or partly rolled up and fastened as disclosed in my co-pending application for patent Ser. No. 23,571, filed April 27, 1948.

On the other hand, it may be desirable to expose only a part of the items to be dried to sun light in which case only part of the canopy need be disconnected from an arm or arms 34 and rolled up toward the post 1, as shown in the latter co-pending application for patent, Ser. No. 23,571.

It is obvious that various changes and modifications may be made to the details of construction without departing from the general spirit of the invention as set forth in the appended claims.

I claim:

1. The supporting means for a combination sun shade and clothes drier including a post and a collar mounted thereon for supporting a sun shade and clothes line sections—the supporting means characterized by a plurality of plates vertically adjustable on the post, each plate having a pair of wings extending outwardly therefrom and an intervening web hugging the post, the wings extending radially from the center of the post, there being notches formed in the wings to form upwardly extending projections to receive portions of the clothes line sections to take up the slack therein, a plurality of sets of arms and links foldable down along the post, each set including one arm and one link disposed between the adjacent wings of two adjacent plates, sets of pivot pins, each set including one pin pivotally connecting the inner end of an arm between one set of said adjacent wings at the upper end of said wings and the other pin pivotally connecting the inner end of a link associated with said latter arm between said adjacent wings at the lower end of said wings whereby said arm and link are held at a fixed distance from one another for all positions thereof, and means releasably anchoring the outer end of the link of each set to its associated arm whereby folding is effected, said collar positioning said plates at predetermined altitudes on said post.

2. The supporting means for a combination sun shade and clothes drier including a post and an abutment mounted thereon for supporting a sun shade and clothes line sections—the supporting means characterized by a bracket, a plurality of sets of arms and links, each set including an arm and a link pivotally connected at their inner ends to said bracket, means releasably anchoring the outer end of each link to its associated arm, said means comprising a pair of ledges on each arm extending inwardly toward each other, a spring pivotally connected to the outer end of each link and slidably supported on said ledges so that when an arm is folded downwardly the end of its link will move toward the outer end of its arm, pins extending through said arms, there being a notch at the outer upper end of each link to receive the pin of an arm, and means for withdrawing a single link, without disturbing any of the other links, against the tension of its spring from anchoring engagement between its notch and the pin of an arm.

3. The supporting means as set forth in claim 2, characterized by the spring being U-shaped

and each leg bent back upon itself normally to form a V-shape, the web between the legs extending across the free end of each link, the free ends of each spring extending into the link, and the portion of the spring resting on the ledge consisting of the leg adjacent said web slidably on, and resting on, a ledge to enable the spring to be compressed when the link is drawn downwardly to clear its notch from the pin of an arm.
